UNITED STATES PATENT OFFICE.

EDWARD L. INGALSBE, OF HARRISON, NEBRASKA.

CROSS-REIN BUCKLE.

1,104,673.

Specification of Letters Patent. Patented July 21, 1914.

Application filed January 25, 1913. Serial No. 744,215.

To all whom it may concern:

Be it known that I, EDWARD L. INGALSBE, a citizen of the United States, residing at Harrison, in the county of Sioux and State 5 of Nebraska, have invented certain new and useful Improvements in Cross-Rein Buckles, of which the following is a specification.

This invention relates to improvements in cross rein buckles, and has for one of its 10 objects to simplify and improve the construction and increase the efficiency and utility of devices of this character.

Another object of the invention is to provide a simply constructed device which may 15 be applied to the drive reins of an ordinary harness without structural change in the harness, and which may be adjusted as required.

With these and other objects in view the 20 invention consists in certain novel features of construction as hereinafter shown and described and then specifically pointed out in the claim, and in the drawings illustrative of the preferred embodiment of the invention. Figure 1 is a plan view of the outlines of portions of a double harness including the driving bits, the drive reins and the cross reins, illustrating the manner of applying the improved buckle device. Fig. 2 25 is an enlarged perspective view of the improved buckle without the straps. Fig. 3 is an enlarged longitudinal sectional view of the parts shown in Fig. 2 with a portion of one of the drive reins and a portion of one 30 of the cross reins arranged therein.

Corresponding and like parts are referred to in the following description and indicated in all the views of the drawings by the same reference characters.

40 In Fig. 1 of the drawings is shown portions of a conventional harness in outline including the bits 10—11, the drive reins 12 and the cross reins 13—14 with the improved buckle connected between the driving reins 45 and the cross reins.

The improved buckle is formed in two frame portions, a relatively long frame portion for receiving the cross rein which comprises side members 15—16 spaced apart, a 50 forward transverse member 17 and a rear relatively heavy transverse member 18. The sides 15—16 are bent intermediate their ends and connected at the bend by a cross bar 19 upon which a buckle strap engaging tongue 55 20 is mounted to swing with its terminal

bearing upon the forward transverse member 17. Extending from the rear transverse member 13 are open loops 21 spaced apart, the loops being narrower than the frame whereby lateral stop shoulders are produced 60 and spaced from the loops, as shown in Fig. 2. The short frame portion of the device is designed to receive a drive rein and comprises side members 22—23, a forward end member 24 and a rear end member 25 and a 65 transverse bar 26 intermediate the ends of the sides 22—23, the sides 22—23 being bent in substantially the same manner as the sides 15—16 of the cross rein receiving frame and limited in their movement in one direction 70 by the stop shoulders 28.

The cross bar 26 is designed to be received within the loops 21 of the cross rein receiving frame, the loops being closed by the blow of a hammer or other suitable implement. Mounted for rotation upon the bar 75 26 between the loops 21 is a strap engaging tongue 27, the free end of the latter tongue bearing upon the terminal member 25 of the frame. 80

One of the improved buckles will be employed at each inner end at the cross reins of their junctures with the drive rein 12, and the drive rein passed beneath the terminals 24—25 and over the loops 21 and engaged 85 by one of its apertures with the tongue 27, and by providing the usual plurality of apertures in the reins the smaller frame may be adjusted longitudinally of the drive rein to any required extent. The cross reins 90 13—14 are passed respectively beneath the terminals 17—18 of the longer frame and over the cross bar 19 and engaged by one of its apertures with the tongue 20, and by providing a plurality of the apertures the 95 cross reins may be adjusted as required.

The billet of the driving rein passes beneath the cross bar 24, and the latter is maintained by the stop shoulders 28 constantly spaced from the cross line receiving 100 frame. Thus all cramping of the billet is avoided, while at the same time the latter is left free to be released when required. By this simple means it will be obvious that the cross reins are effectually coupled in position relative to the drive reins and may be adjusted to any required extent. 105

The improved device is simple in construction, may be inexpensively manufactured of any required size, and plated, 110

japanned or otherwise ornamented or protected, so that the improved buckle corresponds to the metal portions of the harness.

Having thus described the invention, what is claimed is:

A device of the class described comprising a frame including an intermediate transverse bar and loops extending beyond the frame at one end and of less width than the frame, whereby lateral stop shoulders are produced, a tongue swinging upon said bar, and another frame including a transverse

bar and engaged by said loops in position to bear against said stop shoulders and limiting the movement of the last-mentioned frame in one direction and a tongue swinging upon the transverse bar of said last-mentioned frame. 15

In testimony whereof I affix my signature in presence of two witnesses.

EDWARD L. INGALSBE. [L.S.]
